ANTENNA

Edward Brown Newill, Dayton, Ohio, assignor, by mesne assignments, to Radio Corporation of America, New York, N. Y., a corporation of Delaware

Application May 2, 1930, Serial No. 449,221

4 Claims. (Cl. 250—33)

This invention relates to an antenna and more particularly to an antenna mounted on a motor vehicle.

An object of this invention is to provide an antenna for a motor vehicle that may be reeled or rolled up when not in use.

Another object of this invention is to provide means that will facilitate the reeling and unreeeling of the antenna with a minimum amount of work and minimum amount of equipment.

Another object of this invention is to provide an antenna for a motor vehicle that has a plurality of leads or conductors that are not enclosed within the motor vehicle.

Another object of this invention is to provide an antenna for a motor vehicle that when in use is not enclosed within the motor vehicle and that when not in use may be placed under shelter and hidden.

Further objects and advantages of the present invention will be apparent from the following description, reference being had to the accompanying drawings, wherein a preferred embodiment of one form of the present invention is clearly shown.

In the drawings:

Fig. 1 shows a side elevation of an antenna extended or reeled off, as applied to a motor vehicle.

Fig. 2 discloses a plan view of the antenna extended or reeled off.

Fig. 3 shows an end elevation of the reel with the antenna in the reeled position.

Fig. 4 shows a sectional view of the reel as taken substantially on the line 4—4 of Fig. 5.

Fig. 5 is an end view of the reel viewed from the left of Fig. 4.

Fig. 6 is a fragmentary plan view of the reel.

Fig. 7 is a fragmentary view of the link engaging the free ends of the antenna.

Fig. 3 is drawn to a larger scale than Figs. 1 and 2.

Figs. 4, 5, 6 and 7 are drawn to a larger scale than the other figures.

In the drawings, the reference character 10 indicates the body of the car provided with a sun visor 12.

Mounted immediately below the sun visor 12 is a reel 14 supported on the brackets 16 and 18, insulatingly mounted on the body 10. One end of the reel 14 carries a stud 19 passing through the aperture 20 in the bracket 16 and the other end of the reel carries a driving mechanism that includes a motor spring 22, having one end 24 fixedly secured to the reel 14 by a

pin 26 and the other end 28 fixedly attached to a spindle 30, terminating in a rectangular portion 32, nonrotatably mounted in the bracket 18. The spindle 30 is rotatably journaled in the bearings 34 and 36, carried by the reel 14 so that the reel 14 may be rotated with respect to the spindle 32 as will appear more fully later. A tubular member 38 attached to the roll 14 by screws 39 and provided with a flange 40 holds the bearing 36 in a relatively fixed relation with respect to the reel 14.

A plurality of metallic conductors or cables, preferably made from copper, are attached to a metallic strip 44, carried by the reel 14 and extending substantially the entire length thereof. The other end of the leads 42 are carried by a link 46 provided with an eye 48 that engages a hook 50, which may be attached to the cap of the radiator or any other part of the motor vehicle when the leads 42 are reeled off and hooked on a suitable knob 52, carried by the body of the car when the antenna is in the reeled position as best seen in Fig. 3.

A lead or conductor 58 extending from the radio receiver mounted on the motor vehicle is attached to a resilient contact member 60, carried by the bracket 16, frictionally engaging an annular recess 62 of a cap 64, attached to the reel 14 by the stud 19. The cap 64 is preferably soldered to the metallic strip 44 at 66.

From the above description, it can be readily seen that upon the releasing of the link 46 from the hook 50 the motor spring 22, which is normally in tension will rotate the reel 14, thereby winding the conductors 42 upon the reel so as to completely or substantially so hide the antenna from view. When the antenna has been reeled the link 46 may be hooked on the knob 52 so as to rigidly hold the link 46 in position and so as to eliminate any undesirable noise caused by the link dangling. When it is desired to use the antenna, the link 46 may be removed from position disclosed in Fig. 3, the conductors 42 reeled off and the link attached to the hook 50, thereby extending the antenna into position for use.

Although the antenna has been disclosed as being mounted under the sun visor it can be mounted in any other suitable place, such as for example, on top of the body, under the chassis or within the top. The modification disclosed is merely illustrative as any of the others may be used.

While the form of embodiment of the present invention as herein disclosed, constitutes a pre-

ferred form, it is to be understood that other forms might be adopted, all coming within the scope of the claims which follow.

What is claimed is as follows:

- 5 1. An antenna for a radio mounted on a motor vehicle, comprising in combination, a resiliently biased reel attached to the motor vehicle, a plurality of conductors carried on said reel, means electrically connecting said conductors, said conductors being reeled off when extended for use and hooked on said motor vehicle, the conductors converging towards the hooked point on said vehicle when extended for use, and means for at 10 all times connecting the antenna to the radio receiver so as to impress signals thereon.
- 15 2. An antenna for a radio receiver mounted on a motor vehicle, said motor vehicle having a body carrying a sun visor, comprising in combination, a reel attached to the body under the sun visor, 20 an electrical conductor carried by the reel that may be wound on the reel when not in use as an antenna, means for connecting the conductor to

the radio receiver so that signals picked up by the conductor are conducted to the radio receiver and an insulating member for attaching the conductor when extended to the radiator of the motor vehicle.

80

3. An antenna for a radio receiver mounted on a motor vehicle having a top, comprising a plurality of electrically connected conductors, said conductors having one end insulatingly connected to one extremity of the motor vehicle and the other end attached to said top, said conductors extending radially from said extremity to said top.

85

4. An antenna for a radio receiver mounted in a motor vehicle having a top, comprising a reel insulatingly attached to said top, a plurality of electrically connected conductors, each having one end attached to one extremity of the motor vehicle and the other end to said reel, said conductors extending radially from said extremity to said reel.
